PATENTED
SEP 28 1869

John T. Webster

United States Patent Office.

JOHN T. WEBSTER, OF NEW YORK, N. Y., ASSIGNOR TO PAGE, WILDER & CO., OF HALLOWELL, MAINE.

Design No. 3,682, dated September 28, 1869.

DESIGN FOR FLOOR OIL-CLOTH.

The Schedule referred to in these Letters Patent and making part of the same.

To all whom it may concern:

Be it known that I, JOHN T. WEBSTER, of the city of New York, in the county of New York, and State of New York, have originated and designed a new Pattern for Floor Oil-Cloths, or other fabrics, of which the following is a full, clear, and exact description, reference being had to the accompanying drawings, making part of this specification.

The drawings, painted in colors on what is known as design-paper, represent a complete design for floor oil-cloth, or other printed or woven fabrics.

This design, when repeated, consists of octagonal

and square compartments, colored in oak-shades, but other shades may be substituted, if found desirable.

The drawings represent more fully, clearly, and exactly, than any written description can do, the nature and extent of my invention.

What I claim as my invention, and desire to secure by Letters Patent, is—

The design or pattern for floor oil-cloths or other fabrics, herein set forth.

Witnesses: JOHN T. WEBSTER.
THOMAS JEFFERY,
WM. H. BRODHEAD.
